(57) **CLAIM**

The ornamental design for a bot, as shown and described.

DESCRIPTION

FIG. 1 is a top front perspective view of a bot showing our new design, according to a first embodiment;
FIG. 2 is a top rear perspective view thereof;
FIG. 3 is a bottom front perspective view thereof;
FIG. 4 is a bottom rear perspective view thereof;
FIG. 5 is a front elevational view thereof;
FIG. 6 is a right side elevational view thereof;
FIG. 7 is a rear elevational view thereof;
FIG. 8 is a left side elevational view thereof;
FIG. 9 is a top plan view thereof;
FIG. 10 is a bottom plan view thereof;
FIG. 11 is a top front perspective view of a bot showing our new design, according to a second embodiment;
FIG. 12 is a top rear perspective view thereof;
FIG. 13 is a bottom front perspective view thereof;
FIG. 14 is a bottom rear perspective view thereof;
FIG. 15 is a front elevational view thereof;
FIG. 16 is a right side elevational view thereof;
FIG. 17 is a rear elevational view thereof;
FIG. 18 is a left side elevational view thereof;
FIG. 19 is a top plan view thereof; and,
FIG. 20 is a bottom plan view thereof.
The portions illustrated in broken lines form no part of the claimed design.
